UNITED STATES PATENT OFFICE.

MARTIN JELALIAN, OF CRANSTON, RHODE ISLAND.

DIRIGIBLE AIRSHIP FOR MILITARY PURPOSES.

1,241,219.

Specification of Letters Patent. Patented Sept. 25, 1917.

Application filed May 2, 1917. Serial No. 165,958.

To all whom it may concern:

Be it known that I, MARTIN JELALIAN, a citizen of the United States, residing at the city of Cranston, in the county of Providence and State of Rhode Island, have invented certain new and useful Improvements in Dirigible Airships for Military Purposes, of which the following is a specification.

10 The object of the invention is to provide an aerial apparatus of that class which can not be destroyed by fire and which may be conveniently utilized in military operations; the apparatus being provided with a plurality of gas bags located within an inclosing frame divided into a plurality of compartments and each compartment containing a gas bag; layers of fine tin employed between the compartments of said inclosing frame to operate to prevent the fire penetrating from one compartment to the other, when one of the gas bags is occasionally met by fire.

Cylindrical water-tanks are arranged between the said compartments of the gas bags and have water pipe connections projecting outwardly from the inclosing frame of said gas bags designed to be utilized in extinguishing fire, when certain parts of the apparatus are met by fire.

25 The object of the invention is to generally improve this class of air-ship, and it consists in certain and special features of construction and combination of parts, as hereinafter described and claimed.

30 A practical illustration of the invention is represented in the accompanying drawings forming a part of this specification, in which similar characters of reference indicate corresponding parts in all the views.

35 Figure 1 is a side perspective view of my improved apparatus. Fig. 2 is a side perspective detail view of the spring cushion landing device as adapted to be secured upon the bottoms of the cars. Fig. 3 is a side detail view of one of the rudders. Fig. 4 is a side perspective detail view of the winged device. Fig. 5 is a transverse sectional detail view of the apparatus. Fig. 6 is a side detail view of the gangway as arranged between the cars. Fig. 7 is a side detail view of one of the cars, its outer layer partly removed showing its interior construction.

Fig. 8 is a top perspective view of Fig. 7. Fig. 9 is a side perspective elevation of the 55 gas bag inclosing frame, its combined outer layers as partly removed and showing its interior construction. Fig. 10 is a top view of the winged device as arranged with a pair of pull-spring connections. Fig. 11 is 60 a front detail view of one of the revolving propellers.

Referring to Figs. 1 and 9, the device comprises a gas bag inclosing frame —1— provided with alternate outer layers of fine 85 tin —9¹— and canvas —9²—; said frame consisting of a series of flat circular rings —2— arranged transversely to the frame and said rings are provided with equi-spaced perforations —6, 6— arranged in 70 pairs and encircling the same. Tubular rods —3, 3— arranged in pairs encircle the rings —2, 2— and extend longitudinally of the frame —1— and project through said perforations —6, 6— and have one of their ends 75 secured to the perforations formed in the forward end flat circular support —9⁴— and the other ends attached in the same manner to a similar support provided at the rear end of the frame —1— and said longitudinally extending tubular rods have connecting wires —4, 4— arranged between each pair.

80 The frame —1— which surrounds a wire netting —5— is divided into four compartments each compartment contains a gas bag —7—. A space —16⁵— is arranged between each compartment each having a fixed wire platform —10⁸—. Cylindrical water tanks —16¹, 16¹— are mounted upon the wire platforms —10⁶, 10⁶— and have water pipe connections 90 —16⁴ and 55¹, projecting outwardly to the frame —1— to fixed platforms —8, 8—, arranged upon each side of the frame, and also into each car —22— that is carried 95 by the frame —1—.

95 A pair of closely arranged rings —2⁵, 2⁵— similar to the shape of the rings —2— separate the compartments, and each pair forms a space —16⁶, 16⁶— and each space carries a 100 fixed platform —10⁶, 10⁶—.

105 Each pair of rings —2⁵, 2⁵— between the compartments has a series of connecting supports —16⁶—; a wire netting —10⁴— is secured to said supports, and a layer of 105 fine tin is secured to the latter.

The utility of employing layers of tin between the compartments in the manner described is that the same will operate to prevent the fire from penetrating from one compartment to the other, when one of the gas bags is occasionally met by fire.

The utility of arranging water tanks between the spaces has two distinct objects: 1. The water may be utilized for extinguishing fire, when the certain parts of the apparatus is met by the same; 2. When the water is discharged from the tanks at the time when one of the gas bags is met by fire, the apparatus will become lighter and can 15 continue traveling without losing its equilibrium.

The frame 1 is shown as being divided into four compartments, however if desired it may be divided into more than four compartments in the manner as described, with the exception that additional water tanks should be avoided.

The platforms 8 consist of supports 16⁷, 16⁷, having their rear ends rigidly connected to the rings 2⁵, and projecting outwardly therefrom, and said supports 16⁷ have twisted wires 9 connected at their outer ends thereto and extending to the longitudinal supports 11 arranged upon the top of the frame 1, and said twisted wires 9 have connecting wires 12 and a slideable door 16 is arranged in each platform 8, and also a slideable door is formed in the frame 1 opposite each platform 8.

Upon the top of the frame 1 is a gang-way which consists of two longitudinally extending supports 11, 11 and vertically extending supports 10, 10 having their lower ends integral with the rings 2, 2 and their upper ends connected to said longitudinal supports 11 and having connecting wires 10¹, 10¹.

The longitudinal supports 11, 11 have transversely extending connecting supports 10⁶ arranged there between and also connecting wires 10¹, 10¹.

Projecting outwardly from the rear end of the frame 1 is a flat outwardly extending tail portion 17.

Mounted upon a fixed platform 21, forwardly of the mechanism 1 is a gun 20; also mounted upon a platform 19 rearwardly of the mechanism is a gun 18.

Arranged upon the top of the frame 1 is a series of integral eyelets 15, 15.

Located beneath the frame 1 are three cars 22, and as each car is constructed alike an explanation of one of the same will suffice.

The car 22 consists of three metallic frames as frame 52¹, 52³ and 52⁴ which surround the same; a series of vertical supports 35⁶, 35⁶ extending around the car 22

and connected to said frames as at points 35⁷, 35⁷, and a wire netting 51² secured to the same.

Said car 22 is also provided with windows 23 upon both sides of the same for 70 observation purposes.

The bottom frame of the car 22 also carries a series of transversely arranged connecting supports 37², and a wire netting 37 is secured to the latter and 75 a layer of fine tin carried upon the netting.

Extending from the car 22 to the platform 10⁶ arranged within the space 16⁵ between the compartments of the mechanism 1 is an elevating means 80 55²; and secured to the bottom frame 52¹ of said car 22 is a support 25² provided with integral collars 25¹ from which extend shafts 26¹; and a sled form tread member 27 having integral tubes 27¹ is slidably mounted upon the end portions of said shafts 26¹. Expanding coil-springs 26, 26 encircle said shafts 26¹ and have one of their ends secured against the collars 90 25¹ and the other ends attached to the free end portions of the tubes 27¹. Integral strap hooks 29² are carried by the tread member 27 and having strap connections 29¹ extending from said 95 hooks to the support 25².

Extending from the forward end of the car 22 is a flat vertical rudder 29, which extends forwardly from the lower part of a tubular curved shaft 36. Said 100 shaft 36 has an integral vertical flat forwardly projecting portion 49² provided with equi-spaced perforations and also having rudder frame members 51, 51 projecting forwardly from the upper and 105 lower ends thereof, a wire netting 51² being secured to said frame members, and a layer of canvas carried upon each side of the netting.

The shaft 36 is loosely mounted upon a 110 vertically arranged stationary pin 49¹, projects inwardly to the car 22 from the central part thereof and also has a steer-wheel 46 secured at its upper end. Projecting forwardly from the forward end of 115 the bottom of the car 22 is a supporting member 35, which is designed as a support for the vertical stationary pin 49¹ and the latter has its lower end rigidly connected thereto.

Extending transversely to the car 22 behind the steer-wheel 46 is a gun-platform 69. Fixed forwardly upon said platform is a rod 49, and a foot operated rudder-lock 46¹ is mounted upon the 125 central portion of said rod 49 and has a coil pull-spring connection 48, 48 upon each side thereof. Said coil springs encircle the rod 49 and have one of their ends secured to the platform 69 and the other 130

ends attached to the lock —46¹. A portion of a sprocket-wheel —47— integral with the tubular shaft —36— is adapted to receive the free end portion of the rudder lock 5 —46¹, as clearly shown in Fig. 3.

Extending transversely to the car —22— behind the gun-platform —69— is a shaft —68— provided with a revolving propeller —31— at each end thereof. Mounted upon 10 said shaft —68— is a sprocket-wheel —60²— which has a chain connection —60¹— with a sprocket-wheel —59¹— mounted upon a motor-shaft —60—.

Located centrally upon the middle frame 15 —52³— of the car —22— and extending transversely to the same, is a wing-shaft —57²— provided with a crank at each end thereof. Mounted centrally upon said wing-shaft —57²— is a sprocket-wheel —58¹— 20 having a chain connection —60— with a sprocket-wheel —59— mounted upon a motor-shaft 58; also extending transversely to said car —22— and mounted upon the top frame of the same is a shaft —57¹— which 25 is provided with a revolving propeller —31¹— at each end thereof mounted upon said shaft —57¹— is a sprocket-wheel —57— which has a chain connection —66¹— with a sprocket-wheel —66— mounted upon a 30 motor shaft —61—.

Extending transversely to the car —22— behind the shaft —57¹— is a gun platform —69¹—.

Pivotedly connected to the top frame 35 —52⁴— of the car —22— as at points —33²— is a pair of bird-like wings —33— which extend outwardly from each side of the same, and each of said wings consists of a pair of longitudinally extending flat supports —32¹— adapted to conform the curvature of the wing, and said supports —32¹— have vertically projecting flat integral portions provided with equi-spaced perforations to receive transversely extending wing-supports 40 —32⁴—. A wire netting —32⁵— is secured to said supports and a layer of fine tin secured to the netting.

A flat rectangular-shaped support —36²— is located beneath each of said wings and extends longitudinally to the same, and a series of wing-supports —36³— have their lower ends pivotally connected to the support —36²— as at points —36⁴— and the upper ends pivotally united to the supports 55 —32¹— which extend longitudinally to the wings —33—. Pivotedly connected upon the bottom of the rectangular-shaped support —36²— as at point —39²— is a vertical supporting arm —36⁴— provided with an eyelet —55— at its lower end loosely mounted upon the end portion of the wing-shaft —57²— between the collar —54— integral with said shaft —57²— and a removable threaded collar —53— that is secured at the 60 free portion of said shaft.

Located upon the wings —33— is a pair of integral eyelets —33⁴—, and coil-pull-springs —36¹— have their lower ends connected to said eyelets —33⁴— and the upper ends thereof attached to the front end portions of supports —34²— integral with the supports —35²— and —35⁴—; and said pull-spring connections are designed to support said wings to facilitate the upward movements of the same, and said wings are thus constructed to receive up and down motion in the manner of the wings of a bird.

Projecting outwardly from each side of the middle frame —52³— of the car —22— is a plane —54¹— each plane carrying a cylinder —54²— secured upon the bottom of the same by means of supports —54⁶—, and said cylinders are designed to float upon the surface of the water when traveling through the same.

Extending outwardly from the rear of the middle frame —52³— of the car —22— is a flat outwardly extending tail portion 30.

Also extending around the top of the car —22— upon the top frame —52⁴— is a series of vertical supports —35⁴— which carry a main plane —34— composed of a wire netting and a layer of fine tin secured to the same. Outwardly extending supports —35²— have their lower ends connected to the top frame —52⁴— of the car —22— and project through the planes —34— and have their upper ends provided with eyelets; and a pair of longitudinally extending connecting supports —54⁵— located above said plane —34— and which extend upon each side of the frame —1— project through said eyelets and are rigidly connected thereto. A series of flexible twisted wires —14, 14— surround the upper portion of the mechanism —1— and pass through the integral eyelets —15— arranged upon the top of said frame and have their free ends attached to the supports —54⁵— which extend longitudinally to each side of the frame —1— at the lower part thereof, and a wire netting —15¹— is secured to said flexible twisted wires —14, 14—, as shown by Figs. 1 and 5.

Arranged between each car —22— is a gang-way —40, 40— which consists of twisted main wires —31², 31²—, having one of their ends connected to the vertical supports —35⁴— of the car —22— and the other ends attached in the same manner to the opposite vertical support of the opposite car —22—. A series of connecting supports —31⁵— extend transversely to the gang-way and having a wire netting secured to the same. Attaching wires —31⁴, 31⁴— extend from the frame —1— and are connected to main wires —31²—, as clearly shown in Fig. 6.

Each revolving propeller of the car —22— consists of a threaded eyelet —39⁷— having frames —37⁴, 37⁴— integral with and adapted to conform to the exact shape of a usual

revolving propeller, and a wire netting —37⁵— is secured to each of said frames —37⁴— and a layer of fine tin —37⁶— is secured to the netting. The end of the shaft 5 —68— is threaded to receive the eyelet —39¹—, and a threaded collar or a nut may be secured to the end portion of the shaft —68—.

It will be readily understood that however 10 if the certain parts of the car is occasionally met by fire the propellers 31 and 31¹ and the wings 33 can not be affected by the same; or if when the certain parts of the outer layer of the frame —1— or one of the 15 gas bags is met by fire, the arrangement of tin 9¹ and 10² between the compartments will prevent the fire from penetrating from one compartment to the other, and by the arrangement of the propellers and wings as 20 described it will be obvious that the apparatus will have considerable amount of speed and also lifting capacity.

Thus having described my invention, what I claim as new and desire to secure by Letters Patent is:

1. An apparatus of the character described comprising a gas-bag inclosing frame divided into a plurality of compartments, each compartment containing a gas-bag detachably secured within the compartment and adapted to fill out the same, a narrow space between adjacent compartments and said spaces having fixed platforms extending transversely to said inclosing frame, cylindrical water tanks mounted within said spaces and located upon said platforms, and said water tanks having water-pipe connections extending from each end of said cylindrical water-tanks and projecting outwardly to the inclosing frame of said gas bags.

2. An apparatus of the character described comprising a gas bag inclosing frame divided into a plurality of compartments and each compartment containing a gas bag, said frame consisting of a series of flat vertically arranged circular rings located transversely to the frame and provided with equi-spaced perforations arranged in pairs and encircling said rings, a series of tubular rods arranged in pairs, extending longitudinally to said frame and projecting through said perforations of said rings and having one of their ends secured to a flat circular support located centrally at the forward end of the inclosing mechanism of said gas bags and the other ends similarly connected to a small flat circular support provided at the rear end, and a flat outwardly extending tail portion projecting outwardly from the rear end of said mechanism.

3. An apparatus of the character described comprising a gas bag inclosing frame having a plurality of compartments, 65 said frame made of a series of flat vertically

arranged circular rings provided with equi-spaced perforations, a series of longitudinally extending rods arranged in pairs and each pair having connecting wires there between encircling said rings and projecting through said perforations, a pair of closely located rings arranged between adjacent compartments of the frame and said rings having flat vertical circular planes each composed of a series of connecting supports, a wire netting and a layer of fine tin, said planes dividing the compartments of the gas bags and forming a space there between, a wire netting carried by said frame and layers of fine tin secured to the latter between each of said compartments and encircling said spaces.

4. An apparatus of the character described comprising a gas bag inclosing frame divided into a plurality of compartments and having a combined outer layer of fine tin and canvas, a platform arranged between each compartment and having a cylindrical water tank mounted upon the same, fixed platforms projecting outwardly from each side of said inclosing frame, and water pipe connections extending from each end of said water tanks to said outwardly extending platforms and also water pipe connections projecting centrally from the bottom of said cylindrical water tanks into the cars located beneath the frame of said gas bags.

5. An apparatus of the character described comprising a gas bag inclosing frame having spaces arranged between the compartments of the same, similarly constructed cars carried by said frame and located directly beneath said spaces formed between said compartments, ladders extending from said cars through said spaces into fixed platforms located within said spaces and extending transversely to said frame, platforms projecting outwardly from each side of the latter and the same having connecting main twisted wires extending from the outer ends of said outwardly projecting platforms into a longitudinally extending gangway arranged upon the top of said frame.

6. An apparatus of the character described comprising a gas bag inclosing frame provided with a combined outer layer of fine tin and canvas, gas bags secured to said frame and each located within a compartment, three cars carried by said mechanism and located beneath the same and rigidly connected thereto, two revolving propellers and a vertically reciprocating wing upon each side of each of said cars, said revolving propellers composed of a circular threaded eyelet having integral frames projecting therefrom and adapted to conform the exact shape of a usual revolving propeller, a wire netting secured to said frames and a layer of fine tin secured to

the netting, each of said reciprocating wings consisting of a pair of longitudinally extending flat supports adapted to conform to the exact curvature of the wing, and said 5 supports having flat vertically projecting portions provided with equi-spaced perforations, a series of connecting wing-supports extending transversely to said wings and passing through said perforations, a 10 wire netting carried by said supports and a layer of fine tin secured to the netting.

7. An apparatus of the character described comprising a frame having a plurality of compartments and each compartment 15 inclosing a gas bag, cars carried by said frame and located beneath the same, a series of vertically arranged supports integral with and extending around the top of each of said cars said supports carrying 20 flat planes composed of a wire netting and a layer of fine tin, said planes located upon said supports above said cars and supporting said frame of said gas bags, outwardly extending vertical supports extending from 25 the top of each of said cars and projecting through said planes and having longitudinally extending supports secured at their upper ends, a series of twisted flexible supporting wires encircling the upper portion 30 of said frame and passing through integral eyelets formed upon the top of said frame and having their ends attached to longitudinal supports extending upon each side of the frame, and a wire netting secured 35 to said supporting flexible wires.

8. An apparatus of the character described comprising a frame carrying a plurality of gas bags each located within a compartment, a fixed gun platform arranged at the forward end upon the top of said frame and having guns mounted on the same, a gun platform located at the rear end upon the top of said frame and also having guns mounted on the same, a 40 gang-way extending from said rear gun platform to said forward gun-platform, the same consisting of a series of vertical integral supports arranged longitudinally to the mechanism, said vertical supports having 45 two longitudinally extending supports made fast upon their upper ends, connecting wires extending from said longitudinally arranged supports and connected to said frame and a series of connecting supports 50 extending transversely to said gang-way and having their ends connected to said longitudinal supports.

9. An apparatus of the character described comprising a gas bag inclosing 55 frame adapted to support a plurality of gas bags, cars carried by said frame and located beneath the same, each of said cars consisting of metallic frames forming upper, lower and middle frames, said frames having a series of connecting metallic sup-

ports extending from the lower frame and projecting through the middle frame to the upper frame and connected thereto, a wire netting secured to said supports and a layer of canvas secured to the same, longitudinally 70 extending supports bolted upon the bottom of said lower frame, said supports having integral collars and also shafts extending therefrom, sled form tread members having integral tubes slidably mounted upon the 75 end portions of said shafts, expanding coil-springs encircling said shafts and having one of their ends secured against said collars and the opposite ends thereof attached to the free end portions of said tubular 80 members, and integral hooks carried by said tread members and having strap connections extending from said hooks to said longitudinally extending supports.

10. An apparatus of the character described comprising an inclosing frame containing a plurality of gas bags, similarly constructed cars carried by said frame and located beneath the same, a gun platform at the forward end of each of said cars and 90 having guns mounted on the same, gun platforms at the rear ends of said cars, a gang-way extending rearwardly from the rear platform of the forward car to the forward platform of the adjacent car located 95 centrally beneath the frame and also a gang-way extending rearwardly from the rear platform of said opposite car to the forward platform of another car located in the rear beneath said frame, and said gang-ways consisting of a series of twisted main wires 100 having one of their ends attached to a pair of vertical supports provided at the rear upon the top of the forward car and extending longitudinally beneath said mechanism 105 and having their opposite ends connected to similarly arranged vertical supports provided at the forward end of the opposite car, wires extending from the mechanism 110 and connected to said main twisted wires, and also to a pair of main wires forming the bottoms of said gang-ways, connecting wires extending upon the bottom transversely to the gang-ways having their ends connected to said main wires forming the bottoms of 115 said gang-ways, and a wire netting secured to the same.

11. An apparatus of the character described comprising a gas bag inclosing frame having a combined outer layer of fine 120 tin and canvas, cars carried by said frame and rigidly connected thereto, a flat vertical rudder at the forward end of each of said cars, each of said rudders consisting of a curved tubular shaft loosely mounted upon 125 a fixed vertically arranged pin projecting inwardly to the car from the central part thereof and also having a hand-wheel secured at its upper end, said tubular shaft provided with an integral flat vertical for- 130

wardly projecting portion provided with equi-spaced perforations and said projecting portion having rudder members extending forwardly from the upper and lower ends thereof, a wire netting secured to said members and a layer of canvas secured to the same.

12. An apparatus of the character described comprising a gas bag inclosing frame, cars carried by said frame and located beneath the same, two revolving propellers and a vertically reciprocating wing upon each side of each of said cars, a vertically arranged supporting arm beneath each of said wings having its upper end pivotally connected to a flat rectangular-shaped support extending longitudinally beneath said wings, and its lower end provided with an eyelet and loosely mounted upon the end portion of a wing crank shaft located beneath said wings and extending transversely to the car, a series of wing supports, having

one of their ends pivotally connected to said rectangular-shaped support and the opposite ends thereof pivotally united to a pair of longitudinally extending flat supports of said wings, said pair of supports also carrying vertically projecting flat integral portions provided with equi-spaced perforations to receive a series of transversely arranged wing-supports, a wire netting secured to the latter and a layer of fine tin secured to the same, a pair of pull-spring connections arranged upon each of said wings and designed to support the wings and also to facilitate the upward movement of the same.

In testimony whereof I affix my signature in presence of two witnesses.

MARTIN JELALIAN.
